UNITED STATES PATENT OFFICE.

WILLIAM P. BARTEL, OF WALTHAM, MASSACHUSETTS, ASSIGNOR TO AMERICAN LACING HOOK CO., OF WALTHAM, MASSACHUSETTS, A CORPORATION OF NEW JERSEY.

LACING-HOOK-SETTING MACHINE.

SPECIFICATION forming part of Letters Patent No. 729,525, dated June 2, 1903.

Application filed July 17, 1902. Serial No. 115,909. (No model.)

To all whom it may concern:

Be it known that I, WILLIAM P. BARTEL, a citizen of the United States, residing at Waltham, in the county of Middlesex and State of Massachusetts, have invented new and useful Improvements in Lacing-Hook-Setting Machines, of which the following is a specification.

This invention relates to machines for setting lacing-hooks in the uppers of boots and shoes, and is an improvement upon the machine of my invention for which I have made application for Letters Patent, Serial No. 90,148.

15 The object of the invention is to provide a convenient, strong, simple, and durable machine which shall be capable of being run at a high speed and efficiently feed the lacing-hooks to the proper point above the center of 20 the anvil and set the same in the upper of a boot or shoe without injury to or defacement of the hook.

The invention consists in improved mechanism for separating the lacing-hooks upon 25 the raceway and feeding them one by one to a feed-wheel provided with recesses upon its periphery and journaled upon a reciprocating plunger, said feed-wheel carrying the hooks as they are delivered to it one by one to a 30 point above the anvil. The particular means for separating and feeding the lacing-hooks one by one to said feed-wheel consists of a feed-lever which is rocked downwardly across the path of the lacing-hooks upon the 35 raceway and forces the lacking-hooks, preferably with a yielding pressure, one by one into the recesses formed in the periphery of the feed-wheel, holding each lacing-hook in turn before it is taken by the feed-wheel 40 downwardly, so that upon the upward motion of the plunger said lacing-hook will not be thrown upwardly in the raceway into such a position that it will not be fed into the recesses in the feed-wheel.

45 In machines of this class it is very important that the lacing-hooks should be held in the proper position upon the raceway to be taken by the intermittently-rotating feed-wheel; otherwise said lacing-hooks are liable to be caught upon the periphery of the

feed-wheel between the depressions therein, stop the feeding of the hooks, and jam said hooks. The means for feeding the lacing-hooks one by one to the feed-wheel consists, in addition to the feed-lever hereinbefore referred to, of a separator-lever whereby a single hook is taken from a column of hooks on the raceway extending from the separator-lever to the hopper from which the hooks are obtained and dropped one by one down the raceway to said feed-lever.

The invention again consists in specific mechanism for intermittently rotating the feed-wheel and again in the manner in which a guide and driver, comprising a plate having a curved flange integral therewith and extending from one face of said plate at right angles across the periphery of the feed-wheel, is fastened to a reciprocating plunger, whereby a lacing-hook having a little thicker head than the average lacing-hook being used in the machine may be fed by the feed-wheel around the curved flange referred to without injury to the hook.

The invention finally consists in the combination and arrangement of parts set forth in the following specification and particularly pointed out in the claims thereof.

Referring to the drawings, Figure 1 is a front elevation of my improved machine for setting lacing-hooks. Fig. 2 is a side elevation of the same as viewed from the left of Fig. 1. Fig. 3 is a side elevation of the same as viewed from the right of Fig. 1. Fig. 4 is a side elevation of a portion of the machine as viewed from the right of Fig. 1, being a view similar to Fig. 3 with the plunger raised. Fig. 5 is a detail section taken on line 5 5 of Fig. 4, illustrating the mechanism for intermittently rotating the feed-wheel, the parts being shown in their relative positions when the plunger is raised. Fig. 6 is a section similar to Fig. 5, taken on line 6 6 of Fig. 3, showing the relative position of the parts for imparting an intermittent rotation to the feed-wheel when the plunger is lowered. Fig. 7 is a detail side elevation of the lacing-hook-feed lever and parts connected therewith as viewed from the right of Fig. 4. Fig. 8 is an enlarged detail sec-

tion, partly in elevation, taken on line 8 8 of Fig. 1, showing a portion of the plunger and guide and driver and the manner of attaching the said guide and driver to the plunger, 5 the feed-wheel, and the ratchet by which it is driven. Fig. 9 is a detail section, partly in elevation, taken on line 9 9 of Fig. 8. Fig. 10 is a detail view similar to Fig. 4, illustrating the relative location of the feed-lever and 10 separator-lever and the raceway when the plunger is about one-half way between its upper and lowermost position. Fig. 11 is a detail section taken on line 11 11 of Fig. 8.

Like characters refer to like parts throughout the several views of the drawings.

In the drawings, 15 is the frame of my improved lacing-hook-setting machine. 16 is the main driving-shaft, journaled to rotate in bearings 17 17 upon said frame. The driving-shaft 16 is rotated by means of a clutch-pulley 18 of any desirable construction and has a pinion-gear 19 fast thereto and meshing into a gear 20. The gear 20 is fast to a shaft 21, journaled to rotate in bearings 22 25 22 upon the frame of the machine. A plunger 23, guided in ways 24, formed in the frame of the machine, has a vertical reciprocating movement imparted thereto by a crank-pin 25, fast to a disk 26, integral with the shaft 21. The crank-pin 25 is connected by a rod 27 to two links 28 29. The links 28 and 29 are pivotally connected to each other and to the rod 27, the upper end of the link 28 being pivoted upon a pin 30, fast in the frame 30 of the machine, and the lower end of the link 35 29 being connected by a pin 31 to the upper end of the reciprocating plunger 23.

To the lower end of the plunger 23 is fastened a guide and driver 32, consisting of a plate 33, fast to said plunger and having a curved flange 34 integral therewith and projecting at right angles to one face thereof across the periphery of a feed-wheel 35. The plate 33 is fastened to the plunger 23 by a screw 36, which is fast to the plunger 23 and extends through a slot 37, provided in the plate 33. The plate 33 abuts at its upper end against a shoulder 38, formed upon the plunger 23. The slot 37 may be made circular, of 40 a diameter larger than the diameter of the screw 36. The object of fastening the plate 33 to the plunger 23, as hereinbefore described, is to allow a lacing-hook having a head thicker than the average lacing-hook 45 being used upon the machine to be fed around the curved flange 34 by the intermittently-rotated feed-wheel 35 without injury to said lacing-hook or without stopping the machine. This is accomplished by the construction 50 hereinbefore described, the screw 36 being screwed into the plunger tight enough to hold the plate 33 against said plunger by frictional contact; but if a thick-headed lacing-hook is being fed around by the feed-wheel the 55 plate 33 will be moved downwardly a sufficient distance to allow the lacing-hook to pass around the curved flange without injury,

and when the lacing-hook is set, as hereinafter described, against the anvil of the machine the plate will be forced upwardly against the shoulder 38.

The feed-wheel 35 is fast to a shaft 39, journaled to rotate in a bearing 40 at the bottom of the plunger 23. The shaft 39 has fast thereto a ratchet 41 and is intermittently 75 rotated by means of a pawl-lever 42, pivotally supported upon the shaft 39, having a pawl 43 pivotally attached thereto and engaging the teeth of the ratchet 41. The pawl 43 is kept in contact with the teeth of the ratchet 41 by means of a spring 44. A rocking motion is imparted to the pawl-lever 42 upon the shaft 39 by a cam-roll 45, journaled upon said pawl-lever and projecting into a cam-slot 46, provided in the plate 47, adjustably fastened by screws 48 to the frame 15 of the machine. The screws 48 pass through slots 49 in the plate 47, whereby said plate may be adjusted upwardly or downwardly, and thus vary the time at which the pawl-lever is rocked during the upward or downward motion of the plunger.

The lacing-hooks are fed by any appropriate mechanism well known to those skilled in the art from the hopper 50 to a raceway 95 51. The raceway 51 consists of three plates 52, 53, and 54. The plate 52 is stationary and extends from an opening 55 in the hopper 50 downwardly at an angle for a certain distance and then becoming vertical extends downwardly to the feed-wheel 35. The plate 53 is fast to a stationary portion of the machine and extends parallel to the plate 52 from the hopper to the point where said plate 52 becomes vertical. The plate 54 is a reciprocating plate and is fastened to the plunger 23 parallel to the vertical portion of the stationary plate 52, a passage-way for the lacing-hooks being provided between the plates 52 and 53 and between the plates 52 and 54. 100 The lacing-hooks, as hereinbefore set forth, pass from the hopper through the opening 55 down the stationary portion of the raceway to a separator-lever 56, pivoted upon a screw or stud 57, fast to the frame of the machine. The separator-lever 56 is formed in such a manner as to drop the lacing-hooks one by one as said separator-lever is rocked upon its pivot down the vertical portion of the raceway 51. The separator-lever 56 is rocked 105 upon its pivot by a link 58, pivotally connected to a stud 59, fast to the plunger 23. Upon the same stud 59 is also pivoted a lever 60, having an arm 61 thereon connected by a spiral spring 62 to a screw 63, fast to the 110 frame of the machine, and being provided with a segmental projection 64, all so arranged that when the plunger moves downwardly from its uppermost position, Fig. 4, to its lowermost position, Fig. 3, the feed-lever 60 115 will be rocked upon its pivot 59 downwardly and across the path of the lacing-hooks upon the raceway 51, bringing the side 65 of the segmental projection 64 against the lacing-

hook *d* upon the raceway and pressing said lacing-hook downwardly against the lacing-hook *c*, adjacent thereto, with a yielding pressure, as shown in Fig. 3. As the plunger 5 starts upwardly from the position shown in Fig. 3 after having set the lacing-hook *a* in the stock the pawl-lever 42 will be rocked during the first part of said upward motion toward the right, Fig. 6, in the direction of the arrow in said figure, thus rotating the feed-wheel 35 and bringing the lacing-hook *b* into the position formerly occupied by the lacing-hook *a*, the lacing-hook *c* into the position occupied by *b*, and the lacing-hook *d* 15 into the position occupied by the lacing-hook *c*, Fig. 9. During this first part of the upward motion the feed-lever is held by the spring 62 with a yielding pressure against the lacing-hook *d*, so that said lacing-hook is held in a proper position to enter the recess *d'*, Fig. 9, as the feed-wheel 35 is rotated, as hereinbefore set forth. As soon as the plunger has been moved upwardly about one-half 20 of its entire throw, bringing the cam-roll 45 to the position indicated by dotted lines, Fig. 6, the rotation of the feed-wheel 35 will cease and the different parts be brought to the position shown in Fig. 10. The lacing-hook *d* will then be in the position of the lacing-hook 25 *c* in Fig. 9, the lacing-hook *c* in the position of *b*, and the lacing-hook *b* in the position of *a*. At this point in the operation of the machine a stop-pin 66, fast to the feed-lever 60, abuts against the lower end of a stop-plate 30 67, fast to the frame 15, and upon the continued upward motion the feed-lever 60 is rocked upon its pivotal stud 59 from the position shown in Fig. 10 to that shown in Fig. 4, thus moving the segmental projection 64 upon said lever out of the path of the lacing-hooks 35 upon the raceway and allowing the lacing-hook *e* to drop into the position occupied by the lacing-hook *d*, Fig. 4. During the hereinbefore-described upward motion of the plunger the separator-lever 56 is rocked 40 by the link 58 from the position shown in Fig. 3 to that shown, respectively, in Figs. 10 and 4, dropping the lacing-hook *e* and allowing the lacing-hook *f* to descend to the position formerly occupied by the lacing-hook *e*, 45 said lacing-hook *e* resting on the feed-lever projection 64, Fig. 10, and then passing to the position occupied by the lacing-hook *d* in Fig. 4. Upon the downward movement of the plunger the pawl-lever is thrown from the position shown in Fig. 5 to that shown in Fig. 6, ready to again move the ratchet 41 forward one tooth upon the upward motion of the plunger. It will thus be seen that as the 50 feed-wheel is intermittently rotated each lacing-hook as it arrives upon the raceway at the position occupied by the lacing-hook *d*, Figs. 3 and 9, is held downwardly with a yielding pressure by the feed-lever 60, so that 55 no matter how fast the machine may be running said lacing-hook will be held in position to be taken by the feed-wheel at the proper point—viz., one of the recesses, as *d'*, in the periphery of said feed—and hence the feeding of the lacing-hooks will be positive, which 60 is a very essential feature in a machine of this class. Again, it will be seen and understood that as the lacing-hooks above the separator-lever are dropped one by one down the raceway to the position of the lacing-hook *d*, Fig. 4, said lacing-hooks will not be pushed upwardly and downwardly by the reciprocatory motion of the plate 54 of the raceway—another essential point in machines of this class, as it is very objectionable to have the 65 lacing-hooks pushed up and down during the motion of the plunger, resulting in impairing the lacing-hooks and interfering with the practical feeding of the same along the raceway. 70

By the mechanism hereinbefore described 75 for rocking the pawl-lever 42 I avoid excessive spring and wearing of parts such as are ordinarily used, in that the movable actuating parts are reduced to a single cam-roll 45, which enters the cam-groove immediately 80 adjacent to the ratchet, said cam-groove being provided in the stationary plate and said stationary plate being readily adjustable to obtain a slight variation in time of throw of the ratchet by means of the screws 48. 85

The lowermost lacing-hook *a* is driven through the stock and clenched upon an anvil 68 in a manner well known to those skilled in the art. 90

The lacing-hooks may be fed from the hopper 50 to the raceway 51, as hereinbefore set forth, and delivered by any desirable mechanism well known to those skilled in the art. In the present machine I have illustrated this mechanism as consisting of a plate 69, provided with picker-arms 70, delivering near the center, about which said picker-plate rotates, to the raceway 51. The picker-plate 69 is fast to a shaft 71, journaled in the hopper 50. Said shaft 71 has an intermittent rotation imparted thereto by a ratchet 72 and pawl 73, pivoted to a pawl-lever 74, said pawl-lever being rocked upon the shaft 71 by an eccentric-rod 75 and eccentric 76, the eccentric 76 being fast to the shaft 21. 100

The operation of the machine as a whole is as follows: The lacing-hooks are placed in the hopper 50 and are fed out of said hopper through an opening 55 therein by an intermittently-rotated picker-plate 69 onto the raceway 51, passing down said raceway between the stationary plates 52 and 53. Thence following the stationary plate 52 downwardly between said plate 52 and the reciprocatory plate 54 the lowermost lacing-hook first comes 105 to a stop against the periphery of the separator-lever 56. Said lacing-hooks are then dropped, as hereinbefore described, by the rocking of the separator-lever 56 one by one to the lower part of the raceway adjacent to the feed-lever 60. Said feed-lever is rocked, as hereinbefore described, and forces said lacing-hooks, as *d*, downwardly with a yielding pressure until said lacing-hook is taken 110

115

120

125

130

by the intermittently-rotated feed-wheel 35, when it is carried step by step, as shown in Fig. 3, to a position directly above the anvil 68, where it is driven through the stock and clenched upon said anvil beneath the stock in a manner well known to those skilled in the art. The plunger 23, together with the guide and driver, and the raceway-plate 54 are given a vertical reciprocatory movement by means of the crank-pin 25, rod 27, and links 28 and 29.

Having thus described my invention, what I claim, and desire by Letters Patent to secure, is—

15 1. In a machine for setting lacing-hooks, a raceway, a reciprocatory plunger, a feed-lever pivoted to said plunger, and means to rock said feed-lever downwardly across the path of the hooks on said raceway with a yielding pressure for the purpose specified.

20 2. In a machine for setting lacing-hooks, a raceway, a reciprocatory plunger, a feed-lever pivoted to said plunger, and means to rock said feed-lever downwardly across the path of the hooks on said raceway with a yielding pressure during the first part of the upward motion of said plunger for the purpose specified.

25 3. In a machine for setting lacing-hooks, a raceway, a reciprocatory plunger, a feed-lever pivoted to said plunger, and a spring, one end of said spring connected to said lever, the other end thereof to a stationary portion of said machine, all so arranged as to rock said

30 feed-lever downwardly across the path of the hooks on said raceway with a yielding pressure during the first part of the upward motion of said plunger for the purpose specified.

35 4. In a machine for setting lacing-hooks, a raceway, a reciprocatory plunger, a feed-lever pivoted to said plunger, a spring, one end thereof connected to said lever, the other end to a stationary portion of said machine, all so arranged as to rock said feed-lever downwardly across the path of the hooks on said raceway with a yielding pressure during the

40 first part of the upward motion of said plunger for the purpose specified; in combination with a stationary stop so arranged as to engage said feed-lever during the latter part of the upward motion of said plunger and rock said feed-lever upwardly across and out of the path of the hooks on said raceway.

45 5. In a machine for setting lacing-hooks, a raceway, a reciprocatory plunger, a rotary feed-wheel journaled on said plunger, provided with recesses upon its periphery to receive the head of a lacing-hook, mechanism to impart an intermittent rotary movement to said feed-wheel, a feed-lever pivoted to said plunger, and means to rock said lever across the path of the hooks on said raceway and force a lacing-hook downwardly thereon.

50 6. In a machine for setting lacing-hooks, a raceway, a reciprocatory plunger, a rotary feed-wheel journaled on said plunger, provided with recesses upon its periphery to re-

ceive the head of a lacing-hook, mechanism to impart an intermittent rotary movement to said feed-wheel, a feed-lever pivoted to said plunger, and means to rock said lever across the path of the hooks on said raceway and force a lacing-hook downwardly thereon with a yielding pressure into one of said recesses.

55 7. In a machine for setting lacing-hooks, a raceway, a reciprocatory plunger, a rotary feed-wheel journaled on said plunger, provided with recesses upon its periphery to receive the head of a lacing-hook, mechanism to impart an intermittent rotary movement to said feed-wheel, a feed-lever pivoted to said plunger, and a spring one end thereof connected to said lever, the other end to a stationary portion of said machine, all so arranged as to rock said lever downwardly across the path of the hooks on said raceway with a yielding pressure during the first part of the upward motion of said plunger and force a lacing-hook downwardly thereon.

60 8. In a machine for setting lacing-hooks, a raceway, a reciprocatory plunger, a rotary feed-wheel journaled on said plunger, a pawl-and-ratchet mechanism comprising a ratchet, a pawl-lever and a pawl, carried by said plunger and operatively connected to said feed-wheel, a stationary cam-plate provided with a cam-slot immediately adjacent to said pawl-and-ratchet mechanism, and a cam-roll journaled upon said pawl-lever and engaging said cam-slot.

65 9. In a machine for setting lacing-hooks, a raceway, a reciprocatory plunger, a rotary feed-wheel journaled on said plunger, a pawl-and-ratchet mechanism, comprising a ratchet, a pawl-lever and a pawl, carried by said plunger and operatively connected to said feed-wheel, a cam-plate adjacent to said pawl-and-ratchet mechanism, provided with a cam-slot, adjustably fastened to a stationary portion of said machine, and a roll journaled upon said pawl-lever engaging said cam-slot for the purpose specified.

70 10. In a machine for setting lacing-hooks, a raceway, a reciprocatory plunger, a feed-lever pivoted to said plunger, and means to rock said lever downwardly across the path of the hooks on said raceway with a yielding pressure for the purpose specified; in combination with a separator-lever pivoted to a stationary portion of said machine, and means to rock said separator-lever and feed the hooks one by one down said raceway to said feed-lever.

75 11. In a machine for setting lacing-hooks, a raceway, a reciprocatory plunger, a feed-lever pivoted to said plunger, and a spring, one end thereof connected to said lever, the other end to a stationary portion of said machine, all so arranged as to rock said feed-lever downwardly across the path of the hooks on said raceway with a yielding pressure during the first part of the upward motion of said plunger for the purpose specified; in combination with a separator-lever pivoted to a sta-

tionary portion of said machine, and a link, one end pivotally connected to said lever, the other end to said plunger, all so constructed and arranged as to positively rock said separator-lever into and out of the path of the hooks upon said raceway and intermittently feed said hooks one by one down said raceway to said feed-lever.

12. In a machine for setting lacing-hooks, a hopper provided with an outlet for lacing-hooks, a reciprocatory plunger, a rotatory feed-wheel journaled on said plunger, provided with recesses upon its periphery to receive the head of a lacing-hook, mechanism for imparting an intermittent rotary movement to said feed-wheel, a raceway-plate fast to a stationary portion of said machine adapted to guide a lacing-hook from said hopper-outlet to said feed-wheel, a feed-lever pivoted to said plunger, and means to rock said lever downwardly across the path of the hooks on said raceway and force a lacing-hook downwardly thereon with a yielding pressure into one of said recesses.
13. In a machine for setting lacing-hooks, a hopper provided with an outlet for lacing-hooks, a reciprocatory plunger, a rotatory feed-wheel journaled on said plunger, provided with recesses upon its periphery to receive the head of a lacing-hook, mechanism for imparting an intermittent rotary movement to said feed-wheel, a raceway-plate fast to a stationary portion of said machine, adapted to guide a lacing-hook from said hopper-outlet to said feed-wheel, a vertical raceway-plate fast to said reciprocatory plunger and extending upwardly from said feed-wheel adjacent and parallel to said first-named plate, the edges of said raceway-plates separated laterally from each other to form a passage-way therebetween for a lacing-hook, a feed-lever pivoted to said plunger, and means to rock said lever downwardly across the path of the hooks on said raceway and force a lacing-hook downwardly thereon with a yielding pressure into one of said recesses; in combination with a separator-lever pivoted to a stationary portion of said machine, and means to rock said separator-lever and feed lacing-hooks one by one down said raceway to said feed-lever.
14. In a machine for setting lacing-hooks, a hopper provided with an outlet for lacing-hooks, a reciprocatory plunger, a rotatory feed-wheel journaled on said plunger, provided with recesses in its periphery to receive the head of a lacing-hook, mechanism for im-

parting an intermittent rotary movement to said feed-wheel, a raceway-plate fast to a stationary portion of said machine and adapted to guide a lacing-hook from said hopper-outlet to said feed-wheel, a vertical raceway-plate fast to said reciprocatory plunger and extending upwardly from said feed-wheel adjacent and parallel to said first-named plate, the edges of said raceway-plates separated laterally from each other to form a passage-way therebetween for a lacing-hook, a feed-lever pivoted to said plunger, and means to rock said lever downwardly across the path of the hooks on said raceway and force a lacing-hook downwardly thereon with a yielding pressure into one of said recesses.

15. In a machine for setting lacing-hooks, a hopper provided with an outlet for lacing-hooks, a reciprocatory plunger, a rotatory feed-wheel journaled on said plunger, provided with recesses in its periphery to receive the head of a lacing-hook, mechanism for imparting an intermittent rotary movement to said feed-wheel, a raceway-plate fast to a stationary portion of said machine and adapted to guide a lacing-hook from said hopper-outlet to said feed-wheel, a vertical raceway-plate fast to said reciprocatory plunger and extending upwardly from said feed-wheel adjacent and parallel to said first-named plate, the edges of said raceway-plates separated laterally from each other to form a passage-way therebetween for a lacing-hook, a feed-lever pivoted to said plunger, and means to rock said lever downwardly across the path of the hooks on said raceway and force a lacing-hook downwardly thereon with a yielding pressure into one of said recesses; in combination with a separator-lever pivoted to a stationary portion of said machine, and means to rock said separator-lever and feed lacing-hooks one by one down said raceway to said feed-lever.

In testimony whereof I have hereunto set my hand in presence of two subscribing witnesses.

WILLIAM P. BARTEL.
